UNITED STATES PATENT OFFICE.

JOHN DAVIS, OF NEW YORK, N. Y.

BORING-MACHINE.

SPECIFICATION forming part of Letters Patent No. 341,226, dated May 4, 1886.

Application filed January 27, 1886. Serial No. 189,884. (No model.)

To all whom it may concern:

Be it known that I, JOHN DAVIS, a citizen of the United States, residing at the city of Albany, in the county of Albany and State of New York, have invented a new and useful 5 Machine for Boring into Wood or Metal, of which the following is a specification.

My invention relates to improvements in wood and metal working machines; and the 10 object of my invention is to provide an automatic boring-machine which will feed the work to the auger and bore holes into a piece of wood or metal, each hole being removed from the one preceding it at any desired distance, and 15 especially arranged for boring holes into the stiles of window-blinds for the purpose of inserting therein the tenons of the blind-slats.

It is necessary, in the stiles of blinds, that the holes should be equidistant from each 20 other and of the same depth. I attain these objects by the mechanism illustrated in the accompanying drawings, in which—

Figure 1 is a rear perspective view of my machine, showing the driving portion of my 25 machine. Fig. 2 is a plan of my machine. Fig. 3 is a front perspective view of my machine. Fig. 4 is a detail view of the feed mechanism, and Fig. 5 is a detail view of the driving mechanism of my machine.

Similar letters refer to similar parts throughout the several views.

A A' A² represent the frame of my machine, which may be constructed of wood or metal, and may be arranged in any suitable manner 35 to support the various parts of the machine. In the bearing B, I place the shaft C, which carries the loose and tight pulleys C' and C² and the beveled driving-wheel D. The shaft C is supported at its end opposite the bearing B by a suitable bearing, C². The beveled driving-wheel D has a smooth bearing-surface, D', extending from the wheel proper toward the frame A² of the machine, against which the friction-roller K presses when the feed mechanism is in operation. The beveled portion 40 of the driving-wheel D is in close contact with the beveled friction-wheel E, which is attached to the shaft e by set-screw or other suitable means. The shaft e is supported at each end by suitable bearings, e' and e². Near 45 the upper end of the shaft e there is attached

to it the friction-wheel F, which revolves in contact with the friction-wheel G. The friction-wheel G is attached by set-screw or other suitable means to the spindle g', and has sufficient bearing-surface to allow the spindle g' to be raised and lowered, as hereinafter set forth, without destroying the connection with the friction-wheel F. The spindle g' carries the auger H at its lower extremity, and is supported at its upper end by a suitable bearing through which it may be freely moved, and just above the auger H the box g² prevents undue vibration and holds the spindle g' in position. The auger H is attached to the spindle g' by nut and thumb-screw, or in any suitable manner. I thus drive my machine by friction-gearing, avoiding the vibration and uneven motion which is caused by the use of toothed 55 wheels and belts.

I now proceed to describe my feeding mechanism.

The arm i, attached to the frame A of my machine, is provided with a bearing supporting the friction-shaft i², which carries 75 the friction-wheel J, having a smooth periphery, and which is placed in contact with the friction-roller K, when the feeding mechanism is in operation. The shaft i² has a bearing connected to the frame A², and has attached to it 80 on the front of the machine, Fig. 3, the eccentric m, the cam O, and the crank-arm N. The eccentric m has the connecting-rod m' attached to the lever or rock-arm m², which is centered at m², Fig. 4. The end of the rock-arm opposite the connecting-rod m' is attached to the rod m³, which carries the collar m⁴, which collar m⁴ is placed on the spindle g' just below the friction-wheel G. The eccentric m thus imparts a reciprocal motion to the spindle g' and 85 causes it to move the auger H into the wood or metal during the process of boring, and at the proper time to withdraw it from the work and allow the piece operated on to advance the requisite distance. The cam-piece O is attached to the shaft i² and revolves with said shaft, pressing against the bell-crank lever O', which is connected to the rod O². The rod O² is flattened at its upper end, and generally has a rubber head placed thereon, and presses 90 upon the stile or piece to be bored beneath the auger, and holds the stile or piece tightly and

positively in position while the auger is entering the wood or metal, and then descends, removing the pressure, and allows the stile or piece operated on to move forward.

5 The crank-arm N, attached to the shaft i^2 , is provided with a groove, into which a thumb-screw, n, passes, and connects to the crank-arm N the connecting-rod N², which has a slot in its end to allow of the passage of the thumb-screw n. By means of the slot in the end of the connecting-rod and the groove in the crank-arm the thumb-screw may be placed into different positions, and thereby the feed motion of the machine regulated in such a manner that the stile or piece to be bored may be moved a fraction of an inch, or three or more inches, as the nature of the work to be done demands.

The connecting-rod N² is attached to the lever M, which is centered at n^3 , and to the end of which is centered at n^3 , and to the end of which is attached the block M'. The block M' has a tongue, which slides in the groove M', and on the block M' the dog P is movably attached. 25 The crank-arm operates to move the dog P in a lateral direction backward and forward, and provides a feed-motion for my machine.

The rack Q is composed of a notched wooden strip attached to a steel bar, Q'. The steel bar Q' is wider than the notched strip, in order that the rack may pass to and fro through the apertures in the table R without interruption from the notches on the strip, and the bar Q' is placed on its edge rather than on its face, in order that the rack may not sag when it extends from the machine, and precludes the necessity of a stay-bar to support it, as is necessary in racks now in use.

The stile or piece to be bored is attached to the rack by means of a thumb-screw and lug, or in any suitable manner. The rack passes through the table R, which is provided with apertures in each end for that purpose, and the notched portion of it comes in contact with the dog P when the feeding mechanism is in operation. The steel bar Q' extending below the notches on the wooden part of the bar, it slides without interruption in contact with the lower part of the apertures in the table R. 45 The presser-feet S S are attached to the frame A² by screw and slot, in order that they may be adjusted to correspond to the thickness of the piece to be bored, and are for the purpose of holding the stile or piece to be bored in position during the time the auger is entering and leaving the work. The piece of steel L³ is a spring pressing against the side of the stile to keep it close to the frame of the machine, and thereby prevent the line of the holes deviating from the center of the stile. The curved lever T has a handle at its upper end, and at its opposite end carries the small friction-roller K. The friction-roller K is generally made of rubber, but may be a felt-covered or metal roller. The lever T is fulcrumed at T², Fig. 5. I attach a spring, I, to the frame A² and to the lever T, which tends to draw

the lever toward the frame of the machine, and when the lever is drawn as near the frame as the slotted piece I² will allow it to go the feeding mechanism is out of gear. In the slotted piece I² is arranged a thumb-catch, I³, which holds the lever T in place when drawn from the machine, counteracting the force of the spring I, and which may be made to loosen the lever when it is necessary to stop the feeding mechanism. To the lever T is attached the brake T', which presses against the wheel J when the lever is drawn toward the frame A², and tends to prevent the revolution of the wheel J and bring the feeding mechanism to a standstill. When the lever T is drawn from the frame extending the spring I and held by the thumb-catch I³, the friction-roller K comes into contact with the smooth bearing-surface 85 of the driving-wheel D and the wheel J, and the feeding mechanism of my machine is in gear. To the lever T is attached the rod T², which is attached to the bell-crank lever L, which is connected with the upright bar L', upon which rests the end of the dog P. Thus, when the lever T is drawn toward frame of the machine by loosening the thumb-catch I³, the end of the dog P is raised and the dog disengaged from the rack Q, allowing the rack to be drawn back ready to have another stile or piece placed into the machine. The table R, through which the rack Q passes, is open at the bottom, and has a top extending but a short distance of its length. The top R' may be raised or lowered 90 by slot and screw to regulate, with the adjustable presser-feet, the distance between them to correspond with the thickness of the material to be bored. The finger S', attached to the presser-foot S, is arranged as a guide 95 to show the position necessary to place the rack in order to have the first hole come into the proper place in a blind-stile.

In order to bore a stile or piece of wood or metal in my machine, I place the piece or stile 110 on the table R and attach it to the rack Q, arrange the presser-feet S S and movable tabletop R' to correspond with the thickness of the piece to be bored, place the piece in proper position for the first hole, and arrange the 115 length of feed by means of the connecting-rod N² and crank-arm N', draw the lever T from the frame of the machine until it is held by the thumb-catch I³, thus letting the end of the dog drop and bringing the dog into contact 120 with the notches in the rack Q, and at the same time bringing the friction-roller K into contact with the smooth bearing-surface D' of the driving-wheel D and with the friction-wheel J, and the feeding mechanism is in gear. 125 When the belt is placed on the tight pulley C², the beveled driving-wheel D is moved and it communicates motion to the beveled friction-wheel E and friction-wheel F, and the friction-wheel G, which is attached to the spindle carrying the auger H, the auger H is caused to revolve. The beveled driving-wheel D also 130 communicates its motion to the friction-roller

K, and that roller, pressing against the friction-wheel J, causes the shaft i^2 to revolve, and thus puts the eccentric m in motion, causing the spindle g' to move up and down at proper intervals, and thus allowing the auger to enter and leave the piece. The cam O also derives its motion from the friction-shaft i^2 , and causes the clamping-rod O' to press against the under side of the piece when the auger is boring, and to remove the pressure when the piece is being moved forward; and the crank-arm N receives its motion from the friction-shaft i^2 and operates to move the dog P, and therefore the rack Q, in a lateral direction, thus causing the strip, piece, or stile to move forward after one hole has been bored and the auger left the piece the requisite distance for the next hole.

My machine as thus constructed is very simple in its arrangement, and can be run by an unskilled hand, and performs its work accurately and effectively.

I am aware that I have described in my application for a patent for a carving-machine filed November 23, 1885, substantially the same mechanism for causing the knife to revolve that I describe herein for causing the revolution of the auger, and in my said former application I claimed as part of my invention the arrangement of said mechanism in combination with a knife and vise, the knife and vise being necessary elements of a carving-machine. In this application I do not claim as my invention the arrangement of the friction wheels and rollers constituting the driving mechanism for the auger; but

What I do claim as my invention, and desire to secure by Letters Patent, is—

1. In machines for boring into wood or metal, the combination of the driving-wheel D, having a smooth bearing-surface, D', the friction-wheel E, attached to the shaft e, the friction-wheel F, also attached to the shaft e and placed into connection with the friction-wheel G, attached to the spindle g', and the augur H, also attached to the spindle g', with the friction-roller K, attached to the lever T, the friction-wheel J, attached to the friction-shaft i^2 , the eccentric m, attached to the friction-shaft i^2 , the rod m^3 , and collar m^4 , attached to the spindle g', with the cam O, attached to the friction-shaft i^2 , the rod m^3 , and collar m^4 , attached to the spindle g', with the cam O, attached to the friction-shaft i^2 , in contact with the bell-crank lever O', and the clamp-rod O', attached

to the bell-crank lever O', with the crank-arm N, attached to the friction-shaft i^2 , the connecting-rod N ^{2} , adjustably connected to the crank-arm N, the lever M, and the dog P, attached to the block M', all substantially as described, and for the purpose set forth. 55

2. In machines for boring into wood or metal, the combination of a rack composed of a notched wooden portion, Q, and a metal portion, Q', the metal portion extending below the notches on the wooden portion of the rack, with the dog P engaging in the notches 60 in the wooden portion of said rack, with the lever M, carrying the dog P, the connecting-rod N ^{2} , adjustably connected to the crank-arm N, the crank-arm N, attached to the friction-shaft i^2 , all substantially as described, and for 70 the purpose set forth.

3. In machines for boring into wood or metal, the combination of the driving-wheel D, having a smooth bearing-surface, D', the friction-wheel E, attached to the shaft e, the friction-wheel F, attached to the shaft e and in contact with the friction-wheel G, the spindle g', carrying the augur H, and the friction-wheel G, with the lever T, carrying the friction-roller K, the connecting-rod T ^{2} , attached 80 to the bell-crank lever L, the upright bar L', attached to the bell-crank lever L, the spring I, attached to the lever T and to the frame A ^{2} A ^{2} of the machine, and the thumb-catch I ^{3} , with the friction-wheel J, attached to the friction-shaft i^2 , the eccentric m, attached to the friction-shaft i^2 , the rod m^3 , and collar m^4 , attached 85 to the spindle g', with the cam O, attached to the friction-shaft i^2 , in contact with the bell-crank lever O', and the clamp-rod O', 90 with the crank-arm N, attached to the friction-shaft i^2 , the connecting-rod N ^{2} , adjustably connected to the crank-arm N, the lever M, and block M', attached to the dog P, with the rack composed of a notched wooden portion, Q, and 95 a metal portion, Q', the metal portion extending below the notches on the wooden portion of the rack, with the presser-feet S S, attached to the frame A ^{2} A ^{2} of the machine, the adjustable table-top R', and the spring-bar I ^{3} , all 100 substantially as described, and for the purpose set forth.

JOHN DAVIS.
